UNITED STATES PATENT OFFICE.

LENA STRONG AND ALPHONSO B. SMITH, OF SAN FRANCISCO, CAL.

FRUIT-PICKER.

SPECIFICATION forming part of Letters Patent No. 334,486, dated January 19, 1886.

Application filed April 2, 1885. Serial No. 161,067. (No model.)

To all whom it may concern:

Be it known that we, LENA STRONG and ALPHONSO BUDD SMITH, citizens of the United States, and both residing in the city and county 5 of San Francisco, in the State of California, have invented certain new and useful Improvements in Fruit-Picking Implements; and we do hereby declare that the following is a full, clear, and exact description of the same, reference being had to the accompanying drawings, that form part of this specification.

Our invention relates to improvements in fruit-picking devices of the kind that are designed to be placed on the finger for cutting 15 the stem while the fruit is held by the hand, so that both hands of the operator are left free to handle the fruit. Such devices are useful more particularly in grape picking and other operations where the fruit requires to be cut 20 and not pulled.

The accompanying drawings illustrate our invention.

Referring to the said drawings, Figure 1 illustrates the mode of using the device. Fig. 25 2 is a perspective view. Figs. 3 and 4 are cross-sections showing the cutter in two positions. Fig. 5 is a general view of the device taken from the front.

The ring A is produced by taking a strip of 30 sheet metal having suitable stiffness and elasticity and bending it around into tubular form, somewhat smaller at one end than at the other. The edges are lapped over each other, and are left free, so that the size of the ring can be altered by springing the metal, its stiffness being relied on to retain the slope and size without permanently fixing the edges. The ring thus produced is open at both ends, to slip over the finger and leave it exposed at the tip. 35 The cutter B is attached to the ring by a hinge-joint, so that it can be thrown back out of the way when using the hands for climbing and for handling the vines and fruit. This part 40

consists of a cutting-blade, B, set into a plate, b, and provided with a hooked end. The plate 45 is provided with a projection, b^x, which is fitted into a plate or block, c, on the ring having parts c^x c^x, so that a pin, d, being passed through the three parts of the knuckle a hinge-joint is produced. The plate c is fixed in place 50 by solder or by rivets or other fastenings, and the blade is set into a slot in the hinged plate. This connection is made sufficiently stiff to keep the cutter in position, whether forward 55 for action or thrown back out of action, but yet to permit either movement and adjustment of the blade while the device is on the finger. The hinge is made of full length of the ring to give stiffness and prevents twisting, and by driving out the pin the blade is removed for 60 sharpening.

By means of the aforesaid hinge our device can be used on either hand by simply adjusting the blade, so that when in use on the left hand the hook of the blade will be pointing in 65 an opposite direction from the position when in use on the right hand.

Having thus fully described our invention, what we claim, and desire to secure by Letters Patent, is—

In a fruit-picking device, the combination, 70 with the hook-shaped cutting-blade, of the expandable metallic ring, the cutting-blade being hinged to said ring in the manner described, whereby the device can be used on 75 either hand, or the blade thrown back when not in use, substantially as and for the purpose set forth.

In testimony that we claim the foregoing we have set our hands and seals.

LENA STRONG. [L. S.]
ALPHONSO B. SMITH. [L. S.]
